(57) **CLAIM**

The ornamental design for a trellis wire post, as shown and described.

DESCRIPTION

FIG. 1 is a front left top perspective view of a trellis wire post showing our new design;

FIG. 2 is a rear right bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed broken lines shown in the FIGURES represent portions of the trellis wire post that form no part of the claimed design. The dot-dash broken lines define the bounds of the claimed design and form no part thereof. The trellis wire post is shown with multiple symbolic breaks in its length. The appearance of any portion of the trellis wire post between the break lines forms no part of the claimed design.
